DESIGN FOR A COMBINED ASH TRAY AND GAME

Robert L. Chaney, Silver Spring, Md., and Edward
J. Taggart, Washington, D. C.

Application January 31, 1947, Serial No. 136,558

Term of patent 3½ years

(Cl. D85—2)

To all whom it may concern:

Be it known that we, Robert L. Chaney and Edward J. Taggart, citizens of the United States of America, residing in Silver Spring, Maryland, and Washington, D. C., respectively, have invented a new, original, and ornamental Design for a Combined Ash Tray and Game, of which the following is a specification, reference being had to the accompanying drawings, forming part thereof, and wherein:

Fig. 1 is a top plan view of a combined ash tray and game, showing our new design; and

Fig. 2 is a side elevational view with parts thereof broken away for purposes of illustration.

We claim:

The ornamental design for a combined ash tray and game, substantially as shown.

ROBERT L. CHANEY.
EDWARD J. TAGGART.
